(57) **CLAIM**

The ornamental design for a tinder wick sleeve, as shown and described.

DESCRIPTION

FIG. 1 is a perspective view of a tinder wick sleeve, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, shown in a condition of use.

The broken lines in the Figures are for the purpose of illustrating portions of the tinder wick sleeve and environmental structure that form no part of the claimed design.
